(57) **CLAIM**

The ornamental design for a safety glow stick triangle, as shown and described.

DESCRIPTION

FIG. 1 is a front perspective view of the safety glow stick triangle, according to the invention;

FIG. 2 is a front view of the safety glow stick triangle shown in FIG. 1;

FIG. 3 is a rear view of the safety glow stick triangle shown in FIG. 1;

FIG. 4 is a top view of the safety glow stick triangle shown in FIG. 1;

FIG. 5 is a bottom view of the safety glow stick triangle shown in FIG. 1;

FIG. 6 is a left side view of the safety glow stick triangle shown in FIG. 1; and,

FIG. 7 is a right side view, opposite the left side view shown in FIG. 6, of the safety glow stick triangle shown in FIG. 1. The broken lines depict portions of the safety glow stick triangle that form no part of the claimed design.
